DRIVING MECHANISM FOR PLATE-PRINTING MACHINES.

1,253,424.

Specification of Letters Patent. Patented Jan. 15, 1918.

Application filed November 12, 1915. Serial No. 61,032.

To all whom it may concern:

Be it known that I, OSCAR ROESEN, a citizen of the United States, residing at New York city, county of New York, and State 5 of New York, have invented certain new and useful Improvements in Driving Mechanism for Plate-Printing Machines, fully described and represented in the following specification and the accompanying drawings, forming 10 a part of the same.

This invention relates to certain improvements in plate printing machines.

In plate printing machines the printing is done from a flat plate or other surfaces by 15 means of depressed lines. To effect printing with these plates, the whole surface of the plate is first covered with ink so that the lines are effectually filled. The surface of the plate, however, where there are no lines, 20 must be cleaned. To effect this, the plate is wiped in some manner, usually by an endless roll of cloth which is gradually renewed by suitable feeding mechanism. The plate or engraved surface is carried on a suitable 25 support, such as a bed, with which co-operates, to effect the printing, an impression member, usually a cylinder or roll, which is provided with a blanket. To effect a clear 30 impression, and to avoid blurring, the plate or other engraved surface and the co-operating 35 impression member should run at the same speed. The speed of the cylinder, however, relatively to the bed, is, where the cylinder is positively driven, fixed by the 40 diameter of the cylinder. As this cylinder is provided with a blanket, the diameter of the cylinder will vary, and consequently the speed at which it is driven, this variance in diameter being due to overpacking the 45 blanket, or to different thicknesses of the blanket, or because of the fact that after a blanket has been used it compresses and becomes thinner. Where this change in diameter of the cylinder occurs, the slight variance in speed of the cylinder relatively to 50 the bed due to this change will cause a blur in the impression.

It is the special object of the present invention to provide an improved construction 55 whereby the positively driven impression cylinder may be controlled by its contact with the plate on the driving bed, so as to run at the same speed as the plate, the cylinder being permitted to run at a slightly increased or decreased speed relatively to

the speed of its driving mechanism, thus compensating for the small variations in the diameter of the cylinder, due to the causes pointed out above.

For a full understanding of the invention, 60 reference may be had to the accompanying drawings, in which—

Figure 1 is an end view of so much of the impression portion of a plate printing machine as is necessary for an understanding 65 of the invention;

Fig. 2 is a front view of the construction shown in Fig. 1; and

Fig. 3 is a top view, partly in section, of the driving mechanism shown in Figs. 1 70 and 2.

The machine chosen to illustrate the preferred embodiment of the invention is a plate printing machine in which the plate carrying member is a flat bed and the impression member is a roll or cylinder, although it will be understood that the improved driving mechanism may be employed in machines in which the plate carrying and impression members may take different 80 forms.

Referring to the drawings, 1 indicates a plate carrying bed and 2 a plate carried thereon. The plate carrying bed is a positively driven bed, the driving mechanism 85 for which is of any suitable character, and a showing of which has been omitted for the sake of clearness and as being unnecessary for an understanding of the invention. Co-operating with this plate carrying bed is an impression member which in the particular construction shown is a cylinder 3 provided with the usual blanket 4 secured to the cylinder by the usual blanket clamps 5 supported in a slot 6 in the cylinder. This cylinder is mounted on a shaft 7 carried on the usual bearings 8 mounted in the frame of the machine 9. This cylinder is a positively driven cylinder, the power for driving the cylinder being obtained from any suitable 100 source (not shown), this power being communicated to a driver shown as a sprocket wheel 10 mounted on the shaft 7 of the cylinder.

In machines embodying the invention, devices will be provided whereby the cylinder may rotate at a slightly increased or decreased speed relatively to the speed of the mechanism by which it is driven, so that the cylinder when it comes in contact with 110

the plate may roll with the plate at the same rate of speed at which the bed carrying the plate is moved. The specific means for effecting this may be varied. In the particular construction illustrated the driving sprocket 10 to which the driving power is communicated is loosely mounted on the cylinder shaft 7, and there are provided yielding connections between the sprocket 10 and a driven member fixed on the cylinder shaft so that a slightly increased or decreased speed of the cylinder shaft relatively to the sprocket is provided. While these connections may be somewhat varied, in the particular construction illustrated the sprocket 10 is provided with a pair of socketed ears 11, 12 in which are mounted rods 13, 14, these rods being provided with driving heads 15. These rods between the heads and the ears are provided with springs 16 so as to form a yielding connection. Between the driver heads 15 takes a pin 17 projecting from a driven member 18 which may be in the form of a disk, which is fast on the shaft 7, before referred to, and by which the shaft is driven from the sprocket through the connections just described.

With the construction described, having a yielding connection between the loosely running sprocket and the driver, the cylinder may run with the bed at speeds which are slightly increased or decreased relatively to the speed of the driving mechanism, this speed being controlled by the plate on the bed, the cylinder running with the plate

during its traverse under the cylinder, thus effectually preventing a slip or blur due to slight increase or decrease in the diameter of the cylinder. The springs furthermore act to reposition the cylinder after each revolution of the bed, this being necessary due to the fact that the cylinder, being slotted to receive the blanket clamp, must always take on the bed at substantially the same point at each reciprocation of the bed.

While the invention has been shown and described in its preferred form, it will be understood that certain variations may be made in the specific construction by which the results aimed at are accomplished, and it is understood that such changes and variations may be made without departing from the invention.

What is claimed is:

In a plate printing machine, the combination with a driven bed, of an impression cylinder coöperating therewith, a driver sprocket loosely mounted on the cylinder shaft, a driven disk fast on the cylinder shaft, a pin on the disk, and spring-seated heads on the sprocket between which the pin takes, whereby the cylinder may have a slightly increased or decreased speed relatively to the speed of the sprocket.

In testimony whereof, I have hereunto set my hand.

OSCAR ROESEN.
